UNITED STATES PATENT OFFICE.

JOHN J. REINHOLD, OF MARIETTA, PENNSYLVANIA.

STATIONERY.

Application filed October 26, 1921. Serial No. 510,615.

To all whom it may concern:

Be it known that I, JOHN J. REINHOLD, a citizen of the United States, and a resident of Marietta, county of Lancaster, State 5 of Pennsylvania, have invented certain new and useful Improvements in Stationery, of which the following is a specification.

This invention relates to a system of indicating when the end of a sheet is about to 10 appear when writing letters, etc., with the ordinary typewriter.

The uncertainty of when the end of the paper is about to appear when writing full 15 pages on the typewriter is appreciated by nearly everyone who operates a typewriter, therefore, the object of this invention is to provide a new and simple means for indicating to the operator this condition, and which is adaptable to be employed with 20 nearly any type of typewriter.

This invention with its objects will be more fully understood from the following description, taken in connection with the accompanying drawing, forming a part hereof, and in which similar numerals refer to 25 similar parts throughout the several views.

Referring to drawing:

Figs. 1 to 6, inclusive, represent sheets of paper of regular letter size with various 30 forms of perforations which embody the principal features of this invention.

Fig. 7, is a diagrammatic end view of a portion of a typewriter machine.

Fig. 8, is a diagrammatic front view of 35 a portion of a typewriter machine.

Fig. 9, is a modified form of indicating mark.

Referring to Fig. 7, 1 is a platen which carries the paper 2. 3 are pressure rollers 40 which hold the paper 2 against the platen 1 in the usual manner. It is obvious that by turning the platen 1 the paper 2 is fed forward whereby the proper line spacing is obtained. 4 is a paper guard. 5 is a 45 type bar which carries the type 6. 7 is a key lever which operates the type bar 5 when the finger button is pushed down in the usual manner as when operating a typewriter.

50 It is well known that with the regular typewriter construction, it is impossible to see the end 10 of the paper 2, and therefore as the writing proceeds the end 10 sometimes presents itself at the point 11 before it is expected, and the writing has 55 been carried too far on the sheet to present

a good appearance; and further there is no space remaining for the signature of the person who sends the letter.

The new and novel features of this invention is that the sheet 2 is perforated as shown at 8 and 9. These perforations may be very small, so small in fact that they are seldom observed by the person reading the letter, but at the same time are readily observed by the typist, for the reason that it appears as a black spot on the paper when lying against the black surface of the platen 1.

It is now obvious that the typist only 70 need to watch for the perforation 8 in the sheet, which indicates that the desirable space remains on the sheet for closing the letter and for the signature. In the event that the letter is exceptionally long and requires a second sheet, the typist continues 75 to write until the perforation 9 appears, which indicates that there is just sufficient space remaining on the sheet to give a margin of good appearance.

80 In some instances it may be deemed that one perforation is sufficient for the character of writing to be done on the paper; it of course, is then located at the proper point to indicate to the typist where to stop 85 writing, for instance when the perforation reaches a certain point relative to a certain element of the typewriter. A sheet perforated in this manner is represented in Fig. 1, the perforation 12 in full line only being 90 considered.

I have found that it sometimes occurs that one of the characters of the writing covers the perforation when it is located as shown in Fig. 1, and that after this occurs it is 95 hard to observe it, and it may be overlooked entirely and the writing carried too far; to avoid this the perforation may be placed in the margin of the papers as indicated in light dotted lines by 13; then to guide the 100 typist in fixing the paper guide 14, I also place a perforation in the sheet as indicated in light dotted lines at 15, also shown in full lines Fig. 8; this perforation must be on a direct vertical line with the perforation 13.

105 By referring to Fig. 8, it is obvious that the paper guide 14 may be fixed to avoid covering the perforation 15 and that this will assure that the perforation 13 will be 110 apparent to the typist when the end 10 of the paper is about to appear.

Another method for overcoming the above stated objection is to put two perforations in the paper as shown in Fig. 4, and if they are spaced different from that of the line spacing of the typewriter it will be seldom if ever that both perforations will be covered by the writing, and in all probability the typist will observe one of them.

Fig. 3 represents a combination of the system of perforation shown in Figs. 1 and 2, in that it embodies the perforation 15 of Fig. 1 and the perforations 8 and 9 of Fig. 2, the last two perforations named being placed in the left side of the sheet and in a direct vertical line with the perforation 15. The object of this is apparent from the foregoing description.

Fig. 5 is a duplicate of the system of perforations as shown at Fig. 2, except that both ends of the paper are perforated in the same manner; this is desirable on plain paper so that either end may be entered first into the typewriter and the perforations then at the bottom only, being considered for gaging the amount of writing to be put on the sheet.

Fig. 6 is a duplicate of the system of perforations as shown in Fig. 3, except that both sides of the paper are perforated in the reverse manner, then either end of the paper may be entered first into the typewriter, and the perforation along the left hand edge only should be considered for gaging the amount of writing to be put on the sheet.

It is obvious that the perforation might be carried to the extreme edge of the paper where it would produce only a nick in the edge of the paper as shown in Fig. 9, and in many cases give the same result as the other methods herein shown and described; but I prefer the perforation instead of the nick, for the reason that the nick is too readily observed by the person who reads the letter.

The indicating mark is located at the same place on all the sheets of a certain character, but certain typists prefer certain location for this indicating mark which is different from the location desired by others; however, this invention is not limited to the

indicating mark being at any particular location on the sheet except, that it must be within the limits necessary to indicate the conditions which are the objects of this invention.

Having thus described my invention, what I claim and desire to secure by United States Letters Patent is as follows:

1. An article of manufacture, comprising a sheet of paper having a perforation adapted to co-act with some element of a typewriter, said perforation serving as a signal to warn the typist when the end of the sheet is about to appear.

2. An article of manufacture, comprising a sheet of paper having a perforation adapted to co-act with some element of a typewriter, said perforation serving as a signal to warn the typist when writing must cease to have a certain known space remaining on the end of the sheet.

3. An article of manufacture, comprising a sheet of paper having perforations near the lower end thereof and adapted to co-act with some element of a typewriter, said perforation serving as a signal to warn the typist when the end of the sheet is about to appear; and a second perforation near the top of the sheet and in a direct vertical line with the first said perforation and also adapted to co-act with some element of a typewriter, said second perforation serving as a guide to adjust the typewriter elements to assure that first said perforation will present itself to view.

4. An article of manufacture, comprising a sheet of paper having a perforation adapted to co-act with some element of a typewriter, said perforation serving as a signal to warn the typist when writing must cease for allowing sufficient space for a signature; and a second perforation further down the sheet also adapted to co-act with some element of a typewriter, said second perforation serving as a signal to warn the typist when the end of the sheet is about to appear.

In testimony whereof I affix my signature.

JOHN J. REINHOLD.
